J. WAGNER.

SHAFT LOOP.

No. 270,161.

Patented Jan. 2, 1883.

UNITED STATES PATENT OFFICE.

JULIUS WAGNER, OF READING, PENNSYLVANIA.

SHAFT-LOOP.

SPECIFICATION forming part of Letters Patent No. 270,161, dated January 2, 1883.

Application filed October 16, 1882. (Model.)

To all whom it may concern:

Be it known that I, JULIUS WAGNER, of Reading, in the county of Berks and State of Pennsylvania, have invented a new and Improved Shaft-Loop, of which the following is a full, clear, and exact description.

The object of my invention is to provide a new and improved shaft-loop in which the thills or shafts can move freely without undue friction and without chafing the animal.

Reference is to be had to the accompanying drawings, forming part of this specification, in which similar letters of reference indicate corresponding parts in all the figures.

15 Figure 1 is a front elevation of my improved shaft-loop. Fig. 2 is a side elevation of the same. Fig. 3 is a view of the detached U-shaped metal frame B, with its collar, strap-connection, and upwardly-projecting perforated tongues, adapted to be applied to old and worn shaft-loops, as hereinafter described.

A horizontal anti-friction roller, A, is journaled in a U-shaped frame, B, which has the upper ends of its shanks attached to the lower ends of a U-shaped leather loop, C, which is suspended by means of a strap, D, from a harness-saddle, E, in the usual manner. The lower end of the U-shaped frame B is connected, by means of a strap, F, and a loop, F', pivoted to the bottom of the U-shaped frame B, with the belly-band G. If a shaft passes through the shaft-loop, the said shaft will rest on the roller A, and undue friction of the shaft on the shaft-loop will be avoided.

35 The shaft-loops of a harness are generally rocked forward and backward by the movement of the thills or shafts in the said loops, and this rocking movement of the shaft-loop chafes and blisters the sides of the animal.

40 This rocking movement is avoided if the roller A is provided, for the forward and backward movement of the shafts rotates the roller A forward and backward, but cannot rock the loops, as all the movement of the shafts is taken up by the said roller. The said roller A can be made cylindrical or concave, and can be made of hard or soft rubber, or any other suitable material which can be covered with leather, rubber, cloth, or other soft ma-

terial. It is preferably made of soft rubber, 50 so that when the shafts rock up and down the shock produced will be taken up by the rubber roller and will not injure the animal. This is of great importance, especially in two-wheeled carts, where the vertical rocking motion of the shafts is quite considerable, and if continued any length of time would have an injurious effect on the animal.

55 I am aware of the fact that friction-rollers have been placed in various positions in a shaft-loop, and I do not claim such, broadly. My special construction and arrangement of parts, however, present very great advantages, for by making the loop with an inverted-U-shaped leather portion, C, and a U-shaped 65 metal portion, B, and placing the roller in the metal portion, with its axis in horizontal position, the roller fits nicely under the shoulder of the pendent ends of the leather portion to close in the shaft, and the roller cannot be 70 clogged by accumulation of dirt, &c. The most important advantage, perhaps, that my invention possesses is, however, the fact that it permits me to take old partially worn-out shaft-loops, which are only worn at the bottom, 75 and cut off the lower half of them, and then rivet to the lower ends of the remaining portions the upper ends of the U-shaped metal portions. This, it will be seen, permits me to utilize old shaft-loops that are practically worn 80 out and useless and refit them perfectly with my invention, with only the cost of the metal frame and its roller, and the same rivet serves to hold together the two layers of leather of the shaft-loop and to connect it to the perforated end of the U-shaped roller-frame.

85 I claim—

As an improved article of manufacture, the U-shaped metal frame B, having horizontal roller A and strap-connection F', and provided with upwardly-projecting perforated tongues, adapted to be applied substantially as described.

JULIUS WAGNER.
